[57] ABSTRACT

A non-restricting conductor filtering system is provided in the high-pressure barriered area of a high-voltage compressed-gas circuit interrupter to prevent damage to the barrier in the event of blast-valve failure, and a consequent differential-pressure drop across the barrier.

The filtering system not only permits a ready equalization of the pressure across the barrier, in the event of blast-valve failure, but the filtering prevents any small metallic particles from the contact region from entering into the annular high-pressure space between the high-voltage conductor and the surrounding barrier member during subsequent repressurization of the high-voltage, high-pressure area portion of the circuit-breaker.

**NON-RESTRICTING CONDUCTOR FILTERING
SYSTEM FOR A HIGH-VOLTAGE
CIRCUIT-BREAKER**

**CROSS-REFERENCE TO RELATED
APPLICATIONS**

Reference may be made to U.S. Pat. application filed Mar. 9, 1971, Ser. No. 122,453, by Cookson et al., also see Cookson et al., Ser. No. 384,653, filed Aug. 1, 1973, both applications being assigned to the assignee of the instant application. Also, reference may be made to U.S. Pat. application W.E. 42,010, filed Nov. 14, 1972, Ser. No. 306,493, by Cookson et al., and likewise assigned to the assignee of the instant application.

BACKGROUND OF THE INVENTION

In high-voltage circuit-breakers of the type providing a rather restricted high-pressure chamber around the high-voltage conductor, the possible presence of small metallic particles has created the possibility of voltage-flashover between the high-voltage conductor and the relatively closely situated outer grounded conductor. To minimize the hazard of voltage-breakdown between the concentrically arranged conductors, it has been suggested to provide one or more generally tubular insulating barriers to prevent a free space existing between the inner high-voltage conductor and the surrounding outer grounded housing.

To prevent metallic particles from entering the region between the inner high-voltage conductor and the intermediately disposed barrier, it was arranged to somewhat seal the ends of the tubular barrier to the inner high-voltage conductor.

SUMMARY OF THE INVENTION

In accordance with the present invention, to prevent a bursting of the tubular barrier in the event of blast-valve failure, a free venting system has been provided between the annular high-pressure region immediately surrounding the high-voltage conductor, into the tubular high-voltage conductor, and to the region surrounding the contact area. To prevent, however, the entrance of small metallic particles into the inner annular region between the barrier and the inner high-voltage conductor, during repressurization of the high-pressure system, it has been proposed to incorporate a filtering system into such venting, so that the metallic particles will be prevented from entering the annular space between the barrier and the inner high-voltage conductor. As a result, a clean annular space is provided between the inner high-voltage conductor and the intermediately positioned tubular insulating barrier.

Accordingly, it is a general object of the present invention to provide an improved high-pressure system associated with a high-voltage compressed-gas circuit interrupter.

Another object of the present invention is the provision of an improved barrier system having the internal region thereof freely vented to prevent bursting thereof during blast-valve failure.

Another object of the present invention is the prevention of a pressure drop across a barrier in the event of blast-valve failure, and a sudden drop of pressure outside of the barrier.

A more specific object of the present invention is the provision of an improved filtered venting system, inter-

nally of the barrier member, so that a differential pressure drop across the barrier will be prevented, and, additionally, the filtering will prevent the entrance of any small metallic contaminants into the high-pressure system within the barrier member during a subsequent repressurization of the high-pressure system.

Further objects and advantages will readily become apparent upon reading the following specification, taken in conjunction with the drawings.

BRIEF DESCRIPTION OF THE DRAWINGS

FIG. 1 is a side elevational view, partially in vertical section, taken through a high-voltage compressed-gas circuit-breaker incorporating the principles of the present invention;

FIG. 2 is a sectional view taken substantially along the line II—II of FIG. 1;

FIG. 3 is a fragmentary side-elevational view of a portion of the high-voltage and high-pressure system;

FIG. 4 is a detailed sectional view of a portion of the high-pressure system of a modified type of two-break circuit breaker, more clearly illustrating the disposition of the intermediately situated tubular barrier, relevant to the inner high-voltage conductor, and showing the location of the filtered vents but accomodating two series arc-extinguishing assemblages;

FIG. 5 is a fragmentary sectional view illustrating the location and arrangement of the cylindrical filters disposed in diametrically opposite vents provided in the walls of the high-voltage inner tubular conductor;

FIG. 6 is an enlarged sectional view taken along the line VI—VI of FIG. 5;

FIG. 7 is a detailed sectional view of the filter itself;

FIG. 8 is an end elevational view of the cylindrical filter of FIG. 7;

FIG. 9 is a fragmentary sectional view of a portion of the inner high-voltage conductor;

FIG. 10 is a fragmentary vertical sectional view, partly in side elevation, of the separable contact structure for the circuit interrupter, the contacts being illustrated in the closed-circuit position; and

FIG. 11 is an enlarged vertical sectional view taken through the lower end of the arc-extinguishing assembly.

**DESCRIPTION OF THE PREFERRED
EMBODIMENT**

Referring to the drawings, and more particularly to FIGS. 1 and 2 thereof, the reference numeral 1 designates a high-voltage compressed-gas circuit-interrupter. This type of circuit-breaker 1 has been fully described in the following U.S. Pat. Nos.: 3,590,189 — Fischer et al.; 3,639,713 — Fischer et al.; 3,665,133 — Reese et al.; 3,624,329 — Fischer et al.; 3,603,754 — Reese et al.; and 3,596,028 — Kane et al.

Generally, it will be noted that the interrupter section 2 is disposed to the right as viewed in FIG. 1, and the bushing section 3 is located to the left, as illustrated in FIG. 1. Reference may be made to FIGS. 18-20 of U.S. Pat. No. 3,596,028 for a description of how the interrupter and bushing sections may be varied to accommodate various voltage and current ratings of the interrupter.

As set forth in more detail in U.S. Pat. No. 3,596,028, it will be noted that there is provided a high-pressure

region 22, 24, disposed at the lower end of the interrupter, and comprising, generally, an outer metallic tubular grounded housing, designated by the reference numeral 5, as illustrated in FIG. 3, together with an internal concentrically arranged tubular high-voltage conductor, designated by the reference numeral 6 in FIG. 2.

Insulation 8 may be provided around the grounded conductor 5, together with one or more heaters 10 (FIG. 1) to prevent liquefaction of the internally provided gas 12, which may, for example, be sulfur-hexafluoride SF₆ gas.

As set forth in the aforesaid patents, during normal operation, a primary blast-valve 11 opens and gas passes between the tubular contacts 14, 16, and through them in a manner described in U.S. Pat. No. 3,665,133.

In more detail, the movable sleeve contact 14 moves upwardly, during the opening operation, separating from a relatively stationary blast-valve seat 18, and permitting high-pressure gas within the region 20 to pass radially inwardly and upwardly through the region 19 interiorly of the movable sleeve contact 14 and also downwardly into the region 17 within the relatively stationary contact 16. This radially inward flowing blast of high-pressure gas 12, from the region 15 into the regions 17, 19 exhausts into exhaust chambers, designated by the reference numerals 26 and 28, and continues until the secondary blast valves 29 close to halt the continued blasting of gas through the interior of the tubular contacts 14, 16. At this time, the arc (not shown) is extinguished. The exhaust chambers 26 and 28 are pneumatically interconnected by an insulating cylinder 33, through which passes a valve-control rod 34, which is actuated by an operating mechanism at ground potential, and constituting no part of the present invention. Reference may be made to U.S. Pat. No. 3,596,028, issued July 27, 1971, to Frank L. Reese and Richard E. Kane, and assigned to the Westinghouse Electric Corporation, for further details of the operating mechanism, if desired.

For the purpose of understanding the present invention, however, it is merely to be noted that in the closed position of the contacts 14, 16 the primary blast-valve 11 is closed, and the secondary blast valves 29 are open, as illustrated in FIG. 10. During the opening operation, the primary blast-valve 11 opens, as mentioned, permitting high-pressure gas to flow radially inwardly, and upwardly and downwardly through the movable tubular and relatively stationary contacts 14, 16, respectively, until arc extinction ensues, and, subsequently, the secondary blast-valves 29 are closed mechanically. Thus, in the fully open-circuit position of the interrupter of FIG. 10, the contacts 14, 16 are separated, the primary blast-valve 11 is open, the secondary blast valves 29 are closed, and high-pressure gas exists throughout the region 15 and the two regions 17 and 19 interiorly of the separated contacts 14, 16.

Supporting the arc-extinguishing assemblage 36 within the casing structure 33 is a truncated insulating cone-shaped member 40, supported by bolts 42 to a grounded heavy ring-shaped flange member 44, which in turn, is affixed to the lower heavy U-shaped casting member 5, illustrated more clearly in FIG. 3 of the drawings. As shown, the high-voltage conductor 6 passes centrally through the insulating cone-shaped member 40, and is separably connected to spring fin-

gers 46, constituting the lower assembly of the lower exhaust chamber 28, as shown more clearly in FIG. 10 of the drawings.

The movable tubular contact 14 is actuated upwardly by a pair of rod-shaped insulating members 48, actuated by a pneumatic piston structure disposed in the head portion 50 (FIG. 1) of the interrupting assemblage 2. The pair of rod-shaped members 48 have inwardly extending arm portions 52, which first tension compression springs 54 to tend to effect the closing of the secondary blast-valves 29, as illustrated in FIG. 10. However, the secondary blast-valves 29 are latched open, in the manner shown in FIG. 10, by latching members 56 disposed on opposite sides of the casting member 58, and pivotally mounted at 60. After a predetermined opening operation, the upward movement of the arms 52 cams the latching members 56 outwardly, and releases the secondary blast-valve 29 permitting the latter to close under the impetus of the compression springs 54. This latching and control of the secondary blast-valves 29 is more clearly set forth in U.S. Pat. 3,665,133, issued May 23, 1972 to Reese et al. and assigned to the Westinghouse Corporation.

It will be noted, with reference to FIGS. 2 and 10, that should the primary blast-valve 11 for any reason remain "stuck" open, there would result a rapid drop of pressure on the outside 24 of the barrier 20 and through the venting contacts 14, 16. Previously, the tubular insulating barrier 20 was generally somewhat sealed to the upper ends of the high-voltage conductor 6, as illustrated in FIG. 4. As will be obvious, this inner annular space 22, at high pressure, would not drop in pressure as rapidly as the outer space, designated by the reference numeral 24 in FIG. 2, which has much more free communication with the interrupter space. Breakage of barrier 20 was a hazard.

We have discovered that by properly adequately venting the inner high-voltage conductor 6, the pressure will drop within the barrier 20 in annular space 22 as rapidly as it drops on the outside thereof in region 24, and, consequently, there will occur no net differential pressure drop across the insulating barrier 20. The upper ends of the inner high-voltage conductor 6 are, of course, vented as at 6a to the interrupting space 15, as illustrated in FIG. 9.

As shown more clearly in FIGS. 5 and 6, a cylindrical filter 30 is disposed within the diametrically oppositely arranged openings 32 provided in the inner high-voltage conductor, and a pair of nuts 35 and 37 are torqued into position. Adhesive may be utilized in conjunction with the nuts 35, 37 to assure that once they are torqued into place, they will not subsequently move.

FIGS. 7 and 8 show detail views of the cylindrical filter 30. It will be observed that the filter 30 is of mesh construction, and is secured to a pair of opposite end supporter rings 41, which may be placed into position within the inner high-voltage conductor 6 prior to the insertion of the nuts 35, 37 thereinto.

From the foregoing description, it will be apparent that should the secondary blast valves 29 remain, for any reason, stuck in the open position, this would effect a rapid reduction within the outer high-pressure third region 24 with respect to the high-pressure second region 22 interiorly of the insulating barrier member 20. Due to the rapid reduction outside of the barrier 20,

and to the slow leakage inside the barrier member 20, there would result the hazard that the barrier member 20 would fracture, or otherwise suffer damage. By rapidly venting the inner high-pressure region 22 through the vents 30 into the interior 62 of a first high-pressure region with the tubular high-voltage conductor 6, as illustrated in FIGS. 4 and 11, there will result an equalization of pressure between the second and third regions 22, 24, and no resultant differential pressure will be caused to occur across the insulating barrier member 20. It will be observed, with respect to FIG. 4, that the high-voltage conductor 6 is supported by perforated insulating spacers 65, which have a number of vent apertures 65a therethrough, only two openings 65a being shown in each of the two spacers 65 illustrated in FIG. 4. However, due to the number of vents 65a provided through the insulating spacers 65, there is permitted a rapid reduction of pressure within the second region 22 past the two spacers 65 and into the region 22a (FIG. 4), where the pressure may rapidly drop through the ten vent openings 32 provided in the high-voltage conductor 6 and upwardly through the vent openings 6a, as illustrated at the upper end of FIG. 4 of the drawings.

The following requirements are desirable for the filtering system by way of example:

1. Filtration: 40 micron nominal
2. Service: SF₆ gas
3. Flow rate: 12 SCFM at 40 PSIG
4. Max ΔP (clean): 1.0 PSID at rated flow
5. Temp. Range: 0° to 175°F
6. Media: "Microweave" 304L Wire mesh
7. Assemble with silver braze
8. Element will withstand 40 PSIG internal pressure without rupture.

The provision of the filter 30 prevents the entrance of small metallic particles and contaminants into the inner barrier region 22 during the subsequent repressurization of the high-pressure system, should blast-valve failure occur, or, during a normal maintenance operation, when it is desired to repressurize the system.

From the foregoing description, it will be apparent that we have provided an improved venting arrangement, whereby a differential pressure drop will not occur across the cylindrical insulating barrier 20 during a possible blast-valve failure. In addition, we have illustrated the use of a filtering system to prevent the entrance of small metallic particles into the high-pressure second region internally of the cylindrical insulating barrier 20 within annular region 22.

The use of the insulating tubular barrier is set forth in U.S. Pat. application filed Aug. 1, 1973, Ser. No. 384,526, by Cookson et al. and assigned to the assignee of the instant application.

Although there has been illustrated and described a specific structure, it is to be clearly understood that modifications may readily be made therein by those skilled in the art, without departure from the spirit and scope of the invention.

We claim:

1. A high-voltage high-power compressed-gas circuit interrupter, comprising, in combination:
  - a. means defining a high-pressure interrupting region (15);
  - b. a pair of cooperable separable contacts (14, 16) at least one of which (14) is tubular and both contacts

disposed within said high-pressure interrupting region (15);

- c. relatively low-pressure exhausting means (26) pneumatically connected with said one tubular contact (14) to receive an exhausting blast of high-pressure gas from said high-pressure interrupting region (15) during the arc-interruption process;
- d. a hollow metallic high-voltage line-conductor (6) constituting a first high-pressure storage region electrically connected to one of said separable contacts and freely vented to said high-pressure interrupting region (15);
- e. a hollow insulating barrier member (20) surrounding said high-voltage metallic line-conductor (6) and defining an annular sealed second high-pressure region (22);
- f. means defining a third outer high-pressure region (24) freely communicating pneumatically with said high-pressure interrupting region (15) and disposed about said barrier member (20); and,
- g. means defining equalization opening means (32) provided in the wall of said inner hollow metallic high-voltage line-conductor (6) which pneumatically intercommunicates the interior (62) of the high-voltage metallic line-conductor (6) with the annular region (22) within the barrier member (20), whereby a sudden drop of pressure within the outer high-pressure region (24) will not fracture the barrier member (20) because of the permissible rapid equalization of pressure across the barrier member (20) provided by said equalization opening means (32).

2. The high-voltage high-power compressed-gas circuit-interrupter of claim 1, wherein filtering means (30) is provided within the equalization opening means (32) to filter out any small particles from entering the annular second high-pressure region (22) within the barrier member (20).

3. The combination according to claim 1, wherein both of the cooperable separable contacts are tubular and constitute venting contacts.

4. The combination according to claim 1, wherein the hollow metallic high-voltage line-conductor (6) is generally U-shaped and is disposed within a generally U-shaped barrier member (20).

5. The combination according to claim 1, wherein the means defining the outer third high-pressure region (24) includes a generally U-shaped grounded hollow metallic member.

6. The combination according to claim 1, wherein secondary blast-valve means controls the exhausting flow from the high-pressure interrupting region (15) through said one tubular contact and into the low-pressure exhausting means (26).

7. The combination according to claim 1, wherein the equalization opening means comprises a plurality of spaced venting passages (32) leading into the interior of the high-voltage metallic line-conductor (6) from the outer annular high-pressure second storage region (22).

8. The combination according to claim 2, wherein the filtering means comprises one or more tubular cartridge elements (30) having wire screening associated therewith to filter out the particles.

9. The combination according to claim 1, wherein one or more spacer elements (65) are provided along the length of the hollow metallic high-voltage line-

conductor (6) to space the barrier member (20) outwardly from the inner-disposed high-voltage line-conductor (6).

10. A high-voltage high-power compressed-gas circuit-interrupter, comprising, in combination:

- a. means defining a high-pressure interrupting region (15);
- b. a pair of cooperable separable contacts (14, 16) disposed within said high-pressure interrupting region (15);
- c. means defining a relatively high-pressure first region 62 pneumatically communicating with said high-pressure interrupting region (15);
- d. means defining a secondary high-pressure gas-storage region (22) in juxtaposition to said first-mentioned first high-pressure storage region (62) and having an insulating wall portion (20) associated therewith;
- e. means defining a third high pressure storage region (24) freely pneumatically communicating with said high-pressure interrupting region (15); and,
- f. means defining equalization opening means (32) provided in the wall of the first-mentioned, first high-pressure storage region (62) which pneumatically intercommunicates the first high-pressure storage region (62) with the second high-pressure storage region (22), whereby a sudden drop of pressure within the third high-pressure storage region (24) will not fracture said wall portion (20) of the second high-pressure storage region (22) be-

cause of the permissible rapid equalization of pressure across said wall member (20) provided by said equalization opening means (32).

11. The combination of claim 10, wherein filtering means (30) is provided within the equalization opening means (32) to filter out any small particles from entering the second high-pressure storage region (22).

12. The combination according to claim 10, wherein one of the cooperable separable contacts is tubular and vents the high-pressure gas away from the arcing region (15).

13. The combination according to claim 10, wherein the first-mentioned high-pressure storage region (62) is constituted by a generally hollow metallic line conductor (6).

14. The combination according to claim 13, wherein the second high-pressure storage region (22) is constituted by a generally surrounding insulating tubular member (20) in spaced relationship to the inner-disposed tubular member (6).

15. The combination according to claim 10, wherein the third region (24) is at least in part defined by an outer hollow member (5).

16. The combination according to claim 15, wherein the outer member 5 is a metallic grounded tubular member.

17. The combination according to claim 16, wherein the outer tubular member is generally U-shaped in configuration.
